UNITED STATES PATENT OFFICE.

CHARLES G. CURTIS, OF NEW YORK, N. Y.

MARINE STEAM-TURBINE.

1,008,530.

Specification of Letters Patent. Patented Nov. 14, 1911.

Application filed November 19, 1910. Serial No. 593,160.

To all whom it may concern:

Be it known that I, CHARLES G. CURTIS, a citizen of the United States, residing at New York city, in the county and State of New York, have invented a certain new and useful Improvement in Marine Steam-Turbines, of which the following is a specification.

The object I have in view is to simplify and cheapen the construction and repair, and also to increase the efficiency, of marine steam turbines, particularly those having initial jet impulse stages.

My present invention is an improvement upon that set forth in my application for patent of even date herewith (Serial No. 593,159) and consists in a novel construction whereby the principle of balancing the thrusts, including that of the propeller, by reversed drum pressure stages, set forth in that application, is made useful in a marine steam turbine having turbine elements operated at different steam pressures on the same shaft. In a turbine of this character it is important that the two elements of the turbine on the same shaft should be independent of each other with respect to longitudinal expansion and contraction, and hence it is usual to divide the shaft between the two elements and connect the two sections of the shaft together by a coupling permitting a longitudinal slip. The two shaft sections are held against longitudinal movement by independent thrust blocks and the propeller thrust is taken only by one section of the shaft. Heretofore in the construction of marine steam turbines of this character having initial jet impulse stages, and built in two elements complete on one shaft, it has been the practice to employ in the high pressure element a number of wheel stages only, which, having the same steam pressure on opposite sides of the wheels, avoid the production in this element of excessive longitudinal thrusts which would have to be carried by the thrust block and which reduce the steam pressure to the low pressure required to neutralize the propeller thrust; and to employ in the low pressure element a drum pressure stage, having a steam tight pressure head closing the steam space between the drum and the shaft, and producing a thrust opposed to the propeller thrust. The construction indicated is open to the objection of using a considerable number of wheel stages with accompanying diaphragms.

and steam spaces which increase the cost and length of the turbine, and, on account of the inaccessibility of the diaphragm bushings, increase the difficulty and expense of repairs. By my present invention these objections are overcome by replating the wheel stages in the high pressure element largely or partly by drum pressure stages with steam tight pressure heads, which drum stages are reversed and are so proportioned relative to the steam pressures that the thrust produced by one drum stage is practically neutralized by the other drum stage, and the shaft thrust when present is also practically neutralized, at all substantial powers, so that the thrust carried by the thrust block for this element, if any, is small in amount. The propeller thrust is wholly or largely neutralized at all substantial powers in the low-pressure element by a single direct drum pressure stage.

A further feature of the present invention relates to means for adjusting the relative thrusts of the reversed drums in the high pressure element so as to secure a more complete balance in this element under different conditions of steam flow and pressure. This is accomplished by providing a by-pass for the steam, controlled by a valve, around one or each of the drum stages so as to vary the pressure drop between the ends of one or of each of such drum stages to suit the conditions of operation.

Another feature of invention relates to the construction of the improved turbine for a 4-shaft arrangement. In carrying out this part of the invention the turbine is divided into four elements mounted on two shafts, i.e., a high pressure element on one shaft, an intermediate pressure element on the other shaft of the same power as the high pressure element and taking the full flow of steam from the high pressure element, and two low pressure elements (one on each shaft) which receive the steam flow from the intermediate pressure element in multiple. The high and intermediate pressure elements are balanced within themselves by the use of reversed drum pressure stages, while the two low pressure elements receive a low enough steam pressure to wholly or largely neutralize the thrust of the propellers at all substantial powers by the employment in each of a single direct drum pressure stage.

The invention is illustrated as embodied

in two forms of turbine, Figures 1 to 6 showing a turbine composed of a high and a low pressure element complete on one shaft, and Fig. 7 showing a turbine of four elements divided between two shafts.

In the drawings, Fig. 1 is a side elevation, of the high pressure element of the turbine complete on one shaft, with the upper half in longitudinal section on line 1—1 in Figs. 4 and 5; Fig. 2 is a longitudinal section on line 2—2 in Figs. 4 and 5; Fig. 3 is a view similar to Fig. 1 of the low pressure element of the one-shaft turbine; Figs. 4 and 5 are cross-sections on lines 4—4 and 15 5—5 in Fig. 1, respectively, looking in the direction of the arrows; Fig. 6 is an elevation showing the two elements of the one shaft turbine connected together and indicating the location of the thrust blocks for 20 the two elements; and Fig. 7 is a longitudinal half section of a four-element turbine arranged on two shafts.

Referring particularly to Figs. 1 to 6, A and B are respectively the high and low 25 pressure elements of the turbine. I will first describe the high pressure element of the one-shaft form of turbine (Figs. 1, 2, 4 and 5). Its shaft section 7 which carries the rotating parts is preferably stepped 30 down to smaller diameters where it passes through the stuffing boxes, producing shaft thrust areas subject to the steam pressures at the ends of the shell. The sides of the shell or casing are shown at 8, its forward 35 and aft heads at 9, 10 and the stuffing boxes at 11, 12. The high pressure element, as shown, is provided with two initial jet wheel stages. The nozzles 13 of the first stage are carried by the head 9. The wheel 14 of the 40 first stage carries, preferably, a plurality of rows of moving buckets co-acting with stationary intermediate buckets carried by the shell. Following the wheel 14 is a diaphragm 15 supported by the shell and having 45 a bushing or packing surrounding the shaft. The space in front of the diaphragm 15 is large enough to permit the removal and repair of the bushing or packing in segments, and access is given to this space by 50 one or more covered hand-holes or man-holes 16 in the head 9 and by one or more openings 17 in the web of the wheel 14. The diaphragm 15 carries the second stage nozzles 18, and these deliver the steam to the 55 buckets of the second jet wheel stage which are carried by the wheel 19 and by the shell. The wheel 19 is mounted upon the pressure head 20 of the first drum pressure stage, which pressure head is formed and proportioned 60 so as to withstand without change of shape the difference in pressure to which it is subjected. The drum 21 of the first drum stage is supported in part by the head 20 which closes steam tight the space between 65 the drum and the shaft. The first drum

stage carries the steam in the same direction as the initial wheel stages and receives it directly from the second wheel stage. The drum of the first drum stage carries a number of annular rows of buckets separated by 70 annular rows of stationary buckets carried by the casing. These buckets operate on the impulse or on the reaction principle. In either case there is a difference in steam pressure between the admission and discharge ends of the drum stage which is effective on the head 20 to produce an aft thrust on the shaft. As will be understood the admission of steam to the buckets of the first drum stage is a complete peripheral 80 one, while at the wheel stages the nozzles occupy only a part of the peripheries of the wheels. In passing through the wheel stages the steam is reduced in pressure and increased in volume so that a complete peripheral admission can be had at the first drum stage with buckets of a sufficient radial depth to keep the tip clearance leakage 85 within permissible limits.

The radial depth of the buckets of the 90 wheel stages can be made as great as desired because of the fact that a partial peripheral admission (i. e., "jet" admission) is employed in these stages. The use of the initial jet wheel stages also results in a reduction 95 in pressure within the casing head to that which can be practically controlled by the shaft stuffing box.

Following the first drum stage, the steam 100 space between the shell and the shaft is closed by a diaphragm 22 having a bushing surrounding the shaft. A working space is provided in which this bushing or packing may be repaired or replaced in segments, which space is accessible through a covered 105 man-hole or hand-hole 23 in the casing. The diaphragm 22 is made necessary because the steam flow is reversed through the second drum stage. The second drum stage has a drum 24 carrying a number of annular rows of buckets co-acting with annular rows of intermediate buckets carried by the casing, and operating on the impulse or reaction principle. In either case, as with the first drum stage, there is a difference in 110 steam pressure between the admission and discharge ends of the stage which is effective on a steam tight pressure head 25 closing the space between the drum and the shaft and formed and proportioned to withstand the pressure difference to which it is subjected without change of shape. The steam is admitted to the aft end of the second velocity stage by channels 26 in the casing (Figs. 2, 4 and 5) connecting the space in front of the diaphragm 22 with the space aft of the pressure head 25, while the steam discharged from this stage into the space forward of the head 25 is carried 115 back to the chamber 27 in the aft head 120 20. The drum 24 is supported in part by the head 25 which closes steam tight the space between the drum and the shaft. The drum 24 carries a number of annular rows of buckets separated by 125 annular rows of stationary buckets carried by the casing. These buckets operate on the impulse or reaction principle. The admission of steam to the buckets of the second drum stage is a complete peripheral one, while at the wheel stages the nozzles occupy only a part of the peripheries of the wheels. In passing through the wheel stages the steam is reduced in pressure and increased in volume so that a complete peripheral admission can be had at the second drum stage with buckets of a sufficient radial depth to keep the tip clearance leakage 130 within permissible limits.

of the high pressure element by channels 28 (Figs. 1, 4 and 5). The difference in pressure on the shaft thrust areas and the difference in pressure on the first drum stage 5 produce an aft thrust on the shaft, while the difference in pressure on the second drum stage produces a forward thrust on the shaft. By properly proportioning the steam passage areas through the drums, so 10 as to secure the proper pressure drop between the two ends of each drum, and by having each drum of the proper relative area, these thrusts in opposite directions will be practically neutralized or balanced or 15 reduced to a practicable amount at all powers, so that the unbalanced thrust, if any, will be small. In order to secure a more complete balance of the thrusts under 20 different conditions of operation a controllable by-pass may be provided around one or each of the drum stages so as to enable the adjustment of the differences in pressure carried by the pressure heads 20 and 25. A pipe 29 having a valve 30 performs this office for the first drum stage, while an opening 31 (controlled by a valve 32) between the chamber 27 and the admission side of the second drum stage serves to 30 shunt steam around the second drum stage.

The shaft section 7 of the high pressure element A is connected with the shaft section 33 of the low pressure element B by a slip coupling 34. The casing 35 of the low pressure element has fore and aft heads 36, 37, provided with stuffing boxes 38, 39, preferably surrounding reduced diameters of the shaft. One or more pipes 40 convey the steam from the chamber 27 of the high pressure element to the fore head 36 of the low pressure element, and have a slip or expansion joint 41 permitting the relative movement of the two elements. Within the casing of the low pressure element is a drum pressure stage having a number of annular rows of moving and stationary buckets operating on the impulse or reaction principle. The drum 42 of this drum stage is supported from the shaft in part by a steam tight pressure head 43 formed and proportioned to withstand the difference in pressure to which it is subjected without change of shape. The pressure head 43 is subjected 45 on its forward side to the steam pressure existing at the admission end of the drum stage while its rear side is open to the exhaust 44 and hence receives the exhaust pressure. By properly proportioning the steam passage area through this drum stage and by giving it a proper thrust area, the thrust aft produced by it will balance practically, or reduce to a practicable amount, at all powers, the forward thrust of the propeller (not shown) which is carried by 50 the shaft 33. Any unbalanced thrust, one way or the other, will be small. In Fig. 6

the high and low pressure elements are shown assembled, the thrust blocks 45, 46, for the sections 7 and 33 of the shaft being illustrated. These thrust blocks may be located either at the forward or aft end of either element. The reversing turbine is shown as inclosed in the rear end of the casing of the low pressure element. As will be understood, it has a drum pressure stage 75 opposing the propeller thrust.

The turbine shown in Figs. 1 to 6 is useful in any arrangement of one or more propeller shafts, in which it is desired to employ a complete independent turbine on each shaft. 80

A special construction of the turbine adapted for a 4-shaft arrangement is illustrated in Fig. 7, to which reference will now be made. The turbine is divided into four elements, C, D, E and F. The elements C and D are respectively high and intermediate pressure elements, the latter taking the entire flow of steam from the former, while the elements E and F are low pressure elements which receive the steam from the intermediate pressure element in multiple, each taking one-half the flow of steam. The elements C and D are of practically equal power, as likewise are the elements E and F, so that the power developed on each shaft 95 will be the same. The two shaft sections of the high pressure element are indicated at 47, 48, and the slip coupling connecting them is shown at 49. The high pressure element, as shown, has one jet wheel stage 50, although it may have two or more, and two drum pressure stages 51 and 52 separated by a diaphragm 53, and connected so as to have a reversed steam flow by pipes or channels 54. These drum stages have steam tight pressure heads 55, 56, which exert thrusts upon the shaft section 47 in opposite directions so as to practically neutralize the thrust within the high pressure element of the turbine at all substantial powers, as described in connection with the high pressure element A. The low pressure element E, which is mounted on the shaft section 48, is similar in construction to the low pressure element B, already described, having a single direct drum pressure stage proportioned with respect to the area of its steam passage and to its thrust area so as to practically neutralize the propeller thrust at all substantial powers. The shaft sections 47 and 48, it will be understood, are provided with independent thrust blocks, as illustrated in Fig. 6. The intermediate pressure element D receives the full flow of steam from the high pressure element through one or more pipes 57. This element is provided with two drum pressure stages having steam tight pressure heads 60 and 61, separated by a diaphragm 62. The drum pressure stages 58, 59 receive the steam flow in opposite di- 100 105 110 115 120 125 130

rections, the discharge end of stage 58 being connected with the head end of stage 59 by steam channels 63. The reversed drum pressure stages 58, 59 are proportioned so as 5 to produce thrusts in opposite directions and to practically neutralize at all substantial powers the thrusts upon the shaft within this element of the turbine. The rotating parts of the element D are mounted upon 10 the shaft section 64, which is connected with the shaft section 65 by a slip coupling 66. The low pressure element F, which is mounted on the shaft section 65, is similar to the low pressure element E, having a single direct drum pressure stage with a steam tight pressure head adapted to practically neutralize the propeller thrust at all substantial loads. The shaft sections 64, 65 are provided with independent thrust blocks similar 15 to the shaft sections 47, 48. The exhaust from the intermediate pressure element is divided between two pipes 67, 68, which divide the steam flow between the two low pressure elements E and F, giving the large 20 bucket areas required to pass the steam at the low pressure and large volume existing near the exhaust end of the turbine. It will be understood that the shafts shown in Fig. 25 7 are two shafts of a 4-shaft arrangement, and that the other two shafts will be provided with a similarly divided turbine.

What I claim is:—

1. In a marine steam turbine having elements operated at different steam pressures 35 mounted on the same shaft, the combination of reversed drum pressure stages in one element, producing thrusts in opposite directions, and a drum pressure stage in the other element producing a thrust opposed to the 40 propeller thrust, substantially as set forth.

2. In a marine steam turbine having elements operated at different steam pressures mounted on the same shaft, the combination of one or more initial jet wheel stages and 45 reversed drum stages in the higher pressure element, the latter producing thrusts in opposite directions, and a drum pressure stage in the lower pressure element producing a thrust opposed to the propeller thrust, substantially as set forth.

3. In a marine steam turbine, the combination of two elements operated at different steam pressures mounted on the same shaft, a slip coupling in the shaft between the elements permitting the independent longitudinal movement of the two elements, separate thrust blocks for the two shaft sections, reversed drum pressure stages in the higher

pressure element, producing thrusts in opposite directions, and a drum pressure stage in 60 the lower pressure element producing a thrust opposed to the propeller thrust, substantially as set forth.

4. In a marine steam turbine, the combination of a drum pressure stage at the exhaust end of the turbine producing a thrust 65 opposed to and practically the same as the propeller thrust and preceding drum pressure stages reversed with respect to each other and producing opposite and practically equal thrusts, substantially as set forth.

5. In a steam turbine, the combination of reversed drum pressure stages exerting thrusts in opposite directions, and a controllable by-pass for the steam around one 75 or each of such drum stages to adjust the relative thrusts, substantially as set forth.

6. In a marine steam turbine, the combination of high and intermediate pressure elements mounted on different shafts, each 80 having reversed drum pressure stages producing thrusts in opposite directions, and a low pressure element on each shaft having a drum pressure stage producing a thrust opposed to the propeller thrust, substantially 85 as set forth.

7. In a marine steam turbine, the combination of high and intermediate pressure elements mounted on different shafts, each 90 having reversed drum pressure stages producing thrusts in opposite directions and two low pressure elements mounted on the different shafts and receiving the steam flow in multiple from the intermediate pressure element, each of said low pressure elements 95 having a drum pressure stage producing a thrust opposed to the propeller thrust, substantially as set forth.

8. In a marine steam turbine, the combination with two shafts, of a high pressure 100 turbine element on one shaft, an intermediate pressure turbine element having reversed drum pressure stages on the other shaft receiving the full flow of steam from the high pressure element, and two low pressure turbine elements mounted on the two shafts and receiving the steam flow in multiple from the intermediate pressure element, substantially as set forth.

This specification signed and witnessed 110 this 15th day of November, 1910.
